UNITED STATES PATENT OFFICE.

CHARLES M. HINMAN, OF SAUK CENTRE, MINNESOTA.

SLED.

SPECIFICATION forming part of Letters Patent No. 252,107, dated January 10, 1882.

Application filed November 23, 1881. (No model.)

To all whom it may concern:

Be it known that I, CHARLES M. HINMAN, a citizen of the United States, residing at Sauk Centre, in the county of Stearns and State of Minnesota, have invented certain new and useful Improvements in Sleds; and I do hereby declare the following to be a full, clear, and exact description of the invention; such as will enable others skilled in the art to which it appertains to make and use the same, reference being had to the accompanying drawings, and to letters or figures of reference marked thereon, which form a part of this specification.

15 This invention has for its object to furnish an improved knee for sleds; and it consists in the peculiar construction hereinafter fully described.

In the drawings, Figure 1 is a plan of one 20 of my sled-knees and a portion of one of the cross-beams. Fig. 2 is a side elevation of the same. Fig. 3 is a sideview of one of the beams, having the beam-plates attached thereto, and Fig. 4 is a section on line $x x$, Fig. 3.

25 My invention is designed more especially for single-beam bob-sleds; but it is adapted to any kind of sled.

A is one of the knees attached to the runner B. The knee is composed of the two raves $a a$, 30 the upper cross-bar, a' , the lower cross-bar, a^2 , and the two supports $a^3 a^3$, connected to the under cross-bar, a^2 , and extended to the runner B. The standards have their lower ends curved outward and rest on the top of and are made 35 fast to the runner by suitable bolts, b . The cross-bars $a' a^2$ are arranged wide enough apart to provide between them and the upper ends of the standards an opening, A', large enough to receive the end of the cross-beam C. The 40 supports a^3 are provided at their lower ends with shoulders or flanges a^4 , which rest on the top of the runner, and with pins a^5 , (shown in dotted lines, Fig. 2,) which enter holes bored in the runner. When the knee is put in place 45 on the runner and is secured by the bolts b it will be firm in its position and will endure any degree of strain that may be put upon it. I prefer to employ two supports a^3 under the cross-bar a^2 , for thereby greater strength and 50 firmness are given to the knee; but a knee provided with but one support placed at the mid-

dle of cross-bar a^2 will be very strong and durable.

I construct the knee with a curved horn, a^6 , 55 adapted to hold the end of the skid employed when heavy logs are rolled up onto the beams. The inner or bearing surface of the cross-bars $a' a^2$ may be made slightly concave, so as to permit a slight vertical oscillating motion of the runner B when the sled is moving over 60 uneven surfaces.

Each end of the beam C is furnished with the beam-plates $d d$. One of the plates is placed on the upper side, the other on the lower side, of the beam. The beam-plates are formed 65 with the jaws $d' d'$, which project outward on opposite sides of the cross-bars $a' a^2$ and prevent the beam from slipping endwise. The beam-plates are bolted in place. The surface of the plates in the bottom of the channels or 70 ways formed by the jaws $d' d'$ is made with convex bearing-surfaces $d^2 d^2$, as shown clearly in Fig. 4. This permits the runner to have a sufficient and free vertical movement. In connecting the beam and plates to the knee A the 75 plates are first put in the opening A' in the knee, and then the end of the beam is inserted between the said plates, and the latter are made fast by suitable bolts, as shown.

A sled-knee constructed as the one hereinbefore described possesses superior advantages over all ordinary knees. The flaring base given by the outwardly curved raves gives great strength against strain from front to rear, the support or supports under the lower cross-bar, 85 a^2 , prevent any breaking down, while the jaws $d' d'$ on the plates d prevent accident from lateral strain.

The plates d could be constructed without the convex surfaces d^2 , and so that when the 90 beam is inserted between them they would fit snugly in eye A'. Such construction can be adopted where several knees and beams are placed on the same runner and where it is not desired that the runner shall have an independent vertical rocking movement on the end 95 of the beam. In such cases the end of the beam could be made to fit snugly in the eye A', and pins or bolts could be put in position to bear against the sides of the cross-bars $a' a^2$ 100 and have the same function as the jaws $d' d'$.

My sled-knee can be made of iron, cast or

otherwise made into proper form; or it can be shaped out of wood, if desired.

Having thus described my invention, what I claim, and desire to secure by Letters Patent, 5 is—

1. A knee for sleds, composed of the stand-
ards $a a$, having their lower ends flared out-
ward on the top of the runner, and having the
cross-bars $a' a^2$, arranged to provide an eye or
10 opening, A' , to receive the end of the beam,
and having one or more supports, a^3 , under
the cross-bar a^2 and resting on the runner,
substantially as set forth.

2. The combination, with the knee A , pro-
vided with an eye or opening, A' , and the beam
15 C , of the beam-plates $d d$, provided with jaws
 $d' d'$, arranged to embrace the upper and under
cross-bars of the knee and hold the end of the
beam, substantially as set forth.

20 3. The beam-plates $d d$, constructed with

the jaws $d' d'$, and with the transverse convex
bearing-surface d^2 in the space or channel be-
tween the jaws, in combination with the beam
 C and knee A , provided with an eye or open-
ing, A' , the said knee being held so that it has 25
a rocking or swinging motion on the end of
the beam, substantially as set forth.

4. A sled-knee constructed to hold the end
of the cross-beam, and provided with a horn
or curved projection, a^6 , arranged about a 30
level with the upper side of the cross-beam,
substantially as set forth.

In testimony whereof I affix my signature,
in presence of two witnesses, on this 4th day
of November, 1881.

CHARLES M. HINMAN.
